CHIMNEY STRUCTURE

Emil Zimmerman, Everett, Wash.

Application February 15, 1943, Serial No. 475,894

6 Claims. (Cl. 98—78)

The chimney structure to which my invention relates is an improvement over that disclosed in my Patent No. 2,269,050, issued Jan. 6, 1942, for a Chimney cap.

The principal object of my present chimney structure is to increase the draft over that which is afforded by the cap of my above mentioned patent. Additionally the flow of air through the chimney will be less turbulent and less restricted so that the draft conditions are more uniform, as well as being stronger. Furthermore there is less danger of air blowing down the chimney under very unusual wind conditions.

These improved results are obtained by the use of a simplified structure, and one whose appearance blends more attractively with the conventional brick chimney. In addition my present construction is more durable, although less expensive to fabricate.

While the structure illustrated in the drawing is the one which I now prefer, slight modifications in its arrangement and construction may be permissible, provided that its operation is not impaired and the other objects enumerated above are achieved.

Figure 1 is a top perspective view of my chimney showing parts broken away. Figure 2 is a vertical sectional view through the chimney structure illustrating the manner in which it is supported upon a chimney, and Figure 3 is a transverse section through the assembly on the line 3—3 of Figure 2.

While the principle upon which my present chimney structure operates is in general similar to that of my chimney cap disclosed in Patent No. 2,269,050, the arrangement and proportioning of the parts in my present installation produce a superior performance particularly noticeable in the improvement in draft. While the structure may be incorporated in the chimney C as it is fabricated, I prefer that it be formed as an attachable unit, which, for the most part, may be constructed of concrete or other ceramic material, to be superimposed upon the chimney.

Such a unit, which is shown in the drawing, includes a body 1 having outside dimensions corresponding to those of the chimney C, and a flue opening at least as large as that of the chimney proper and aligned with it. The upper end of the chimney or auxiliary unit is closed by a cover 2, which preferably can be lifted off for access to the internal parts. Within the body and spaced below the cover is a dished deflector 3, which is preferably made of sheet metal. This deflector is a hollow frusto-pyramidal pan, the sides of

which flare upward from a bottom of substantial area. While the deflector illustrated is rectangular it is intended that the term "frusto-pyramidal" or "truncated pyramidal" be understood in its generic sense to embrace any polysided structure including a frusto-conical or truncated conical deflector, which is the special case for a pyramid having an infinite number of sides.

The body 1 is usually square, although it may be rectangular or of other shape, and at its upper end includes a notch or aperture 10 in each side. If the body is circular it should include at least three such apertures, and, although there may be more than four, a greater number is unnecessary. 15 In any case it is desirable that the chimney or body top be open at all sides. If the openings are defined by notches, pillars 11 dividing adjacent notches will be formed, one upstanding from each corner of the body 1 to serve as supports for cover 2.

The cover 2 has imperforate partitions 20 projecting downward from it between each pair of adjacent openings 10 and extending centrally, diagonally across the upper end of the chimney. 25 These partitions project downward somewhat below the lower edges of such openings, and extend a short distance into the deflector 3. Preferably these partitions are cast or molded integral with the cover 2, when fabricated of concrete or similar material, and converge toward its center. The cover may become progressively thicker toward its central portion 21 to provide surfaces 22 between the partitions curving inwardly and downwardly from the cover edges. Preferably 30 the cover margin projects outward somewhat beyond the outer surface of the body 1, for reasons which will be described hereafter.

The dished deflector 3 may be supported in any suitable manner centrally within the body 1, but 40 preferably is suspended from the lower edges of openings 10 by fingers 30 projecting outward from the center of each side edge of the deflector. These may fit into notches in the body walls forming the lower edges of the openings or be 45 hooked to fit over them. The upper edge of each deflector side is spaced inwardly from the inner surface of the corresponding flue wall to leave a smoke passage between these two elements. As shown best in Figure 2 the partitions 20 not only 50 extend downward below the lower edges of apertures 10, but also project a short distance down into the deflector 3.

In order to obtain the most efficient operation from a structure of this general type the arrangement and proportion of the parts are important,

and this is particularly true of the shape, size and location of the deflector within the chimney. In particular if the best draft conditions are to be obtained the air flowing laterally through the chimney should be deflected as little as possible during its passage, while still obtaining good draft. Moreover the air flow should be as smooth and uniform as can be obtained.

To provide a smoke passage between the flue walls and the deflector 3 its upper dimension is smaller than the internal width of the chimney, being perhaps 70% of the chimney width so that 15% is allowed on each side of the deflector for upward passage of the smoke. The upper edge of the deflector should be spaced slightly below the lower edge of the openings 10, but preferably not more than the width of the smoke passage, and may, for example, be about 10% of the internal width of the chimney below the lower edge of such opening. This size and disposition of the deflector, in conjunction with the projecting margins of the cover, insure that the air flowing into one of the side openings will pass into the deflector, and no turbulence can occur between the deflector and the chimney wall which would blow down the chimney or disturb smooth upward flow of the smoke through it.

The depth of the deflector is not particularly critical, but the important consideration is that it be sufficiently shallow so that the air will not be deflected from a horizontal course any more than necessary in passing through the chimney. In flowing from the deflector outward, however, the air should have a sufficient upward component to create a good draft by aspirating action. It is particularly important that the area of opening between the floor of the deflector and the cover 2 be sufficiently large that the flow is not restricted. Also when the air strikes either the cover or the deflector it should not be driven into a pocket, but rather always be directed generally on through the passage. Thus the bottom of the truncated deflector should be of substantial area and of fairly uniform dimensions in all directions, preferably being about one-third of the internal width of the chimney. The depth of the deflector may be somewhat greater, being perhaps 40% of the internal chimney width. Thus although the transverse air passage contracts in lateral extent toward the center of the chimney because of the convergence of the partitions its vertical extent increases despite the downward curvature of surfaces 22 on the cover. The outer edge of the cover, the lower edge of an opening 10, and the lower corner of the deflector between its bottom and opposite side wall will be generally in line if such dimensions are used, and aligned with the intermediate deflector edge.

In operation, although the partitions are fixed, wind will blow into at least one and not more than two of such openings in a rectangular chimney structure, and will flow out through the opening or openings on the opposite side of the chimney. Thus air may blow somewhat downward into an opening 10 in one side of the chimney directly into the deflector, which, by impact against its opposite, upwardly inclined side, will divert the air for flow out through the opening on the opposite side of the chimney. Ordinarily, however, the wind will blow more nearly horizontally into the opening, and be guided downward into the deflector by striking one of the curved surfaces 22. The curvature of these surfaces is considerably less than a quadrant, so that air is not diverted directly downward. Turbulent ac-

tion in a pocket at the bottom of the deflector is thus avoided, for at most the air will strike the floor of the truncated deflector at an acute angle, to flow along it and up the opposite side of the deflector, and thence out through the opposite opening 10 with very little disturbance.

Consequently the flow through the deflector, being substantially unrestricted, smooth, and not turned directly downward even in the most extreme case, will be substantially uniform. No air is trapped and pressure cannot build up within in the bottom of the deflector, which would act to obstruct or disturb smooth flow of air through the structure, so that there is no tendency to force incoming air to flow down the chimney instead of through the transverse passage between the deflector and the cover. On the other hand, the flow of air emerging from the deflector will produce a strong aspirating action upon the combustion gases and smoke rising through the chimney, to draw them outward through the discharge opening 10 with the air. It is thus unnecessary for the smoke passage between the upper edge of the deflector and the inner chimney wall to be as large as would otherwise be required.

What I claim as my invention is:

1. In combination, a chimney having openings in its opposite sides near the top thereof, a cover member closing the top of said chimney, a hollow truncated pyramidal deflector having a bottom of substantial area and sides flaring upwardly and outwardly from said bottom, the upper edges of said deflector sides being spaced slightly inwardly from the inner walls of said chimney to afford a smoke passage therebetween, and being disposed below the lower edges of the side openings in said chimney a distance less than the spacing of such edges from the chimney walls, and partition means fixed within said chimney in a position interposed between such opposite side openings and extending from said cover member downward into said deflector slightly below the upper edges of its sides.

2. In combination, a chimney closed at its top and laterally open on all sides adjacent its top, partition means fixed within said chimney centrally thereof and extending from its closed top downward completely through and to a level below its laterally open portion, a hollow truncated pyramidal deflector having a bottom disposed well below said partition means and of a width equal to at least substantially one-third the corresponding width of the flue passage and sides flaring upwardly and outwardly from its bottom, the edges of said deflector sides being spaced slightly inwardly from the inner walls of said chimney to afford a smoke passage therebetween, and being disposed below the lower edges of the side openings in said chimney a distance less than the spacing of such edges from the chimney walls but above the lower edge of said partition means.

3. In combination, a chimney having openings in its opposite sides near the top thereof, a cover member closing the top of said chimney, a hollow truncated pyramidal deflector having a flat bottom of substantial area and sides flaring upwardly and outwardly from said bottom, the upper edges of said deflector sides being spaced slightly inwardly from the inner walls of said chimney to afford a smoke passage therebetween, and being disposed below the lower edges of the side openings in said chimney a distance less than the spacing of such edges from the chimney walls, fixed partition means within said body interposed between such opposite side openings and extend-

ing from said cover member downward into said deflector slightly below the upper edges of its sides, said cover member defining a curved surface at one side of said partition means to deflect downward into said deflector air entering one such side opening, and further defining a curved surface at the other side of said partition means for guiding outward through the other side opening air emerging from beneath said partition means and flowing out of said deflector.

4. In combination, a rectangular chimney having an opening in each side thereof near its top, a cover member closing the top of said chimney, a hollow truncated pyramidal deflector having a rectangular bottom of a width equal to substantially one-third the corresponding width of the flue passage, and sides flaring upwardly and outwardly from such bottom, the depth of such deflector being slightly greater than the minimum width of the bottom, the upper side edges of said deflector being parallel to and spaced inwardly from the corresponding adjacent inner walls of said chimney, to afford a smoke passage therebetween, and being disposed below the lower edges of said lateral openings a distance less than the spacing from such walls, and two intersecting fixed imperforate partitions disposed diagonally of said chimney, extending from said cover member downward to a level slightly below the upper edges of said deflector sides.

5. In combination, a rectangular chimney having openings in its opposite sides near the top thereof, a cover member closing the top of said chimney and projecting laterally beyond the sides thereof, a hollow truncated pyramidal deflector having a flat rectangular bottom of substantial area and sides flaring upwardly and outwardly from said bottom, the projection of said

cover, the height of such a chimney opening, the depth of said deflector, and the width of its bottom being such that a marginal edge of the cover, the lower edge of the adjacent chimney opening and the corner between the deflector bottom and its inclined side opposite such cover edge are disposed in substantially linear relationship, and imperforate partition means fixed within said chimney in a position interposed between such opposite side openings and extending from said cover member downward into such deflector slightly below the upper edges of its sides.

6. In combination, a rectangular chimney having openings in its opposite sides near the top thereof, a cover member closing the top of said chimney and projecting laterally beyond the sides thereof, a hollow truncated pyramidal deflector having a flat rectangular bottom of substantial area and sides flaring upwardly and outwardly from said bottom, the projection of said cover, the height of such a chimney opening, the depth of said deflector, and the width of its bottom being such that a marginal edge of the cover, the lower edge of the adjacent chimney opening, the upper edge of the deflector side adjacent to such opening, and the corner between the deflector bottom and its inclined side opposite such cover edge are disposed in substantially linear relationship, the upper edges of said deflector being spaced from the adjacent inner walls of the chimney to afford a smoke passage therebetween, and imperforate partition means fixed within said chimney in a position interposed between such opposite side openings and extending from said cover member downward into such deflector slightly below the upper edges of its sides.
